UNITED STATES PATENT OFFICE

EWEN COOPER DUFF, OF NEW YORK, N. Y., ASSIGNOR TO KOPS BROS. INC., OF NEW YORK,
N. Y., A CORPORATION OF NEW YORK

APPAREL GARMENT

Application filed August 3, 1928. Serial No. 297,342.

This invention relates to an apparel garment and more particularly to that type of garment in which a brassière or bust supporter member is associated with a girdle. 5 I am aware that heretofore bust supporters or brassières and girdles have been worn as separate and independent garments. Heretofore also provision has been made for uniting a brassière with a girdle to form a combined 10 garment thereof. In the use of this type of garment there is little or no difficulty in the front portions of the brassière being maintained in position relatively to the front portion of the girdle. In instances, however, 15 where the back of the brassière is fixedly connected to the back of the girdle the parts of the garment are not adapted to adjust themselves to various movements of the body of the wearer and consequently in certain positions, 20 for example, in stooping, the garment is exceedingly uncomfortable. Moreover, when the brassière and girdle are separate garments the back portion of the brassière has a tendency in certain movements of the body to 25 creep or ride upwardly and when this occurs there is only one way in which to return it to its normal position, that is, by manually pulling it back to place.

The object of my invention is to overcome 30 the inconveniences and difficulties hereinbefore referred to and in doing so the garment made in accordance with the invention comprises a combined brassière and girdle preferably open at the side and in which the front 35 member of the brassière is fixedly connected to the front portion of the girdle while the back portion of the brassière is adapted to underlie the upper back portion of the girdle and is connected thereto merely by sets of 40 yielding or elastic straps by means of which the back portion of the brassière is returned and normally maintained in its intended position relatively to the back member of the girdle.

45 In the drawings Fig. 1 is a perspective view showing the use of the garment made in accordance with this invention,

Fig. 2 is an elevation, on an enlarged scale, of the back of the garment, and

Fig. 3 is a perspective view on a still larger

scale looking at the garment from one side thereof which is open to thereby more clearly disclose the structure to which the invention particularly relates.

The garment as illustrated in the drawing 55 comprises a brassière member and a girdle. The girdle is constructed to include a front member 10 which tapers downwardly and in the upper portion thereof may be suitably fitted with a series of spaced stays 11. The 60 girdle also includes a right side member including an inelastic section 12 and an elastic section 13, together with an elastic insert 14. The section 12 and the insert 14 are suitably connected to each other and to the front member 65 10 and likewise the section 12 is suitably connected to the elastic section 13 on the right side of the girdle. In the left side of the girdle there is a side member comprising a section 15 of inelastic material, a section 16 70 of elastic material and an insert of elastic material indicated at 17. The inelastic section 15 and the insert 17 are connected to each other and to the front member 10 and the lower portions of the adjacent edges of the 75 inelastic section 15 and the elastic section 16 are connected to each other as indicated at 18 by a reinforcing strip and suitable lines of stitching that extend from the lower edges of these members a predetermined distance upwardly to a point indicated at 19 above which the parts of the girdle, as well as the parts of the brassière as hereinafter described are 80 open and fitted with suitable series of hooks 20 and eyes 21 forming the closure for the 85 garment.

The girdle also includes a back member which as illustrated is constructed to comprise sections 22, 23 and 24 all made of inelastic material and suitably shaped and connected to each other and to the elastic sections 13 and 16 of the side members. In the upper central portion of the back member I employ an elastic insert 25, the upper edge 90 portions of the centrally disposed section 22 of the back member being cut away, as indicated at 26, making V-shaped gore portions 95 filled by parts of this elastic insert for increasing the yieldability of the upper central back portion of the girdle. The upper 100

edge of the insert 25 is coincident with the upper edge of the back section of the girdle and the lower edge of this insert is indicated at 26'.

The brassière portion of the garment includes a front member 27 which is preferably coextensive circumferentially with the front member 10 and sections 12 and 15 of the girdle. This front member of the brassière 10 along its lower edge is suitably fixedly connected to the upper front edge of these parts of the girdle, namely, the front member 10 and the sections 12 and 15, and in suitable positions the front member 27 of the brassière 15 may be provided with darts 28 and 29 to properly shape the same to the body of the wearer. The brassière member also includes a right hand side section 30 and a left hand side section 31, together with a back 20 section 32. Circumferentially these side sections of the brassière are substantially coextensive with the elastic sections 13 and 16 and extend below the upper edges of the same where they taper downwardly as indicated 25 at 33 and 34 and may be of slightly greater extent circumferentially than these elastic sections in order to provide for a predetermined and limited yielding effect of the same in conforming to the waist line of the wearer.

30 The back of the brassière member is connected at its right hand side to the adjacent edge of the side section 30 by a reinforcing strip 35 and lines of stitching 36 which are the same as those employed to connect the 35 section 24 of the girdle to the elastic section 13 thereof. Similarly the back member of the brassière at the left side thereof is connected to the adjacent edge of the side section 31 by a reinforcing strip 37 and lines of 40 stitching 38 which are the same as those employed to connect the section 23 of the girdle to the elastic section 16 thereof. It will be understood that the reinforcing strip 35 and the lines of stitching 36 also connect the 45 back member and right hand side member of the brassière to the girdle from the point 39 at the lower edge of the brassière to the upper edge of the girdle. In like manner the reinforcing strip 37 and the lines of stitching 38 connect the back member and left hand side member of the brassière to the girdle from the point 40 at the lower edge of the brassière to the upper edge of the girdle. The lower edge of the back member of the 50 brassière is indicated by the line 41 and as will be apparent this portion of the brassière as well as the side members 30 and 31 thereof extend below the upper edge portions of the girdle.

55 60 As illustrated the back of the brassière member is reinforced by a member 42 lying on the outer side thereof and suitably connected thereto and also by a larger reinforcing member 43 lying on the inner side thereof and suitably connected thereto. Other-

wise than as described the lower portion of the back and side members of the brassière is not fixedly connected to the girdle. In order, however, to maintain the back of the brassière in position relatively to the girdle 70 and when shifted to return the back of the brassière to place, I employ sets of elastic tapes, indicated at 44 and 45.

At their lower ends these tapes are attached to the back of the girdle appreciably 75 below the lower edge of the brassière while their upper ends, which are preferably spaced, are suitably connected to the lower edge of the back member of the brassière preferably at the end portions of the reinforcing member 42. These tapes preferably diverge from their lower points of connection to the back member of the girdle to their upper points of connection to the back member of the brassière. This structure 80 makes it possible for the back member of the brassière to shift its position on the body of the wearer, depending upon the movements and position of the same, and also causes the return of the back portion or member of the 85 brassière to its normal position relatively to the girdle when the body of the wearer returns to its normal position.

As illustrated the garment may be provided with suitable hose supporters, for example, hose supporters 46 and 47 depending from the lower edges of the sections 12 and 15 in the front of the garment, hose supporters 48 and 49 depending from the lower edges of the side portions of the garment, and hose supporters 50 and 51 depending from the lower edges of the back of the garment. Also, as illustrated, the brassière member of the garment may be fitted with suitable shoulder straps 52 and 53 which have their 100 extremities suitably connected to the upper portions of the front and back members of the brassière.

I claim as my invention:

1. In an apparel garment, a step-in girdle 110 comprising a front member, a back member, and side members of elastic material, a brassière comprising a front member, a back member and side members all of inelastic material, the lower edge portions of the side 115 members and the back member of the brassière underlying the upper portions of the side members and back member of the girdle, the distant upper edge portions of the back member of the girdle being permanently connected to the distant edges of the lower portions of the back member of the brassière along substantially vertical lines each extending from the upper edge of the girdle to the lower edge of the brassière the back member of the girdle being further permanently connected to the back of the brassière by elastic straps, the side members of the girdle being otherwise unconnected to the side 120 members of the brassière.

2. In an apparel garment, a step-in girdle comprising a front member, a back member, and side members of elastic material, a brassière comprising a front member, a back member and side members all of inelastic material, the lower portions of the back and side members of the brassière underlying the upper portions of the back member and side members of the girdle, the distant upper longitudinal edge portions of the back member of the girdle being permanently connected to the distant lower underlying longitudinal edge portions of the back member of the brassière by substantially vertical lines of stitching extending from the upper edge of the girdle to the lower edge of the brassière, the side members of the girdle being otherwise unconnected to the side members of the brassière, and means for permanently and yieldingly connecting the underlying edge portion of the back member of the brassière to the back member of the girdle, permitting the back member of the brassière to shift relatively to the back member of the girdle and to be returned and normally maintained in an initial position relatively thereto.

3. In an apparel garment, a girdle comprising a front member, a back member, and side members of elastic material, a brassière comprising a front member, a back member and side members all of inelastic material, the lower portions of the back and side members of the brassière underlying the upper portions of the back member and side members of the girdle, the distant upper edge portions of the back member of the girdle being permanently connected to the distant lower edge portions of the back member of the brassière from the upper edge of the girdle to the lower edge of the brassière, the side members of the girdle being otherwise unconnected to the side members of the brassière, and sets of elastic tapes each set thereof lying in a position distant from the center of the back member of the girdle, at one end permanently connected thereto, with the parts thereof diverging upwardly and connected to the lower edge portion of the back member of the brassière to apply an evenly distributed tension in the back member of the brassière, permitting the same to shift relatively to the back member of the girdle and causing the same to be returned and normally maintained in an initial position relatively thereto.

Signed by me this 23 day of July, 1928.
EWEN COOPER DUFF.
